US00D873786S

(12) **United States Design Patent** (10) Patent No.: **US D873,786 S**
(45) Date of Patent: ** Jan. 28, 2020

(54) **BUMPER FOR VEHICLE**

(71) Applicant: **Ningbo Geely Automobile Research & Development Co., Ltd.**, Ningbo (CN)
(72) Inventor: **Armand Bentzen**, Göteborg (SE)
(73) Assignee: **NINGBO GEELY AUTOMOBILE RESEARCH & DEVELOPMENT CO., LTD.**, Ningbo (CN)

(**) Term: **15 Years**

(21) Appl. No.: **29/659,640**

(22) Filed: **Aug. 10, 2018**

(30) **Foreign Application Priority Data**

Feb. 13, 2018 (EM) 004706786
